UNITED STATES PATENT OFFICE.

GEORGE H. BERRY, OF SHELTON, CONNECTICUT, ASSIGNOR TO INTERNATIONAL SILVER COMPANY, OF MERIDEN, CONNECTICUT, A CORPORATION OF NEW JERSEY.

DESIGN FOR A BEVERAGE MIXER OR SIMILAR ARTICLE.

Application filed April 26, 1926. Serial No. 17,459. Term of patent 7 years.

To all whom it may concern:

Be it known that I, GEORGE H. BERRY, a citizen of the United States, residing at Shelton, county of Fairfield, State of Connecticut, have invented a new, original, and ornamental Design for a Beverage Mixer or Similar Article, of which the following is a specification, reference being had to the accompanying drawing, forming a part thereof.

The drawing shows a perspective view of a beverage mixer showing my new design.

I claim:

The ornamental design for a beverage mixer or similar article as shown.

GEORGE H. BERRY.
